UNITED STATES PATENT OFFICE.

WILLIAM PRELLWITZ, OF EASTON, PENNSYLVANIA, ASSIGNOR TO INGERSOLL-RAND COMPANY, OF NEW YORK, N. Y., A CORPORATION OF NEW JERSEY.

FLUID-FEEDING ATTACHMENT FOR HOLLOW DRILL-STEELS.

1,069,288.

Specification of Letters Patent.

Patented Aug. 5, 1913.

Application filed January 19, 1909. Serial No. 473,091.

To all whom it may concern:

Be it known that I, WILLIAM PRELLWITZ, a citizen of the United States, and resident of Easton, in the county of Northampton 5 and State of Pennsylvania, have invented a new and useful Improvement in Fluid-Feeding Attachments for Hollow Drill-Steels, of which the following is a specification.

This invention has for its object to provide a fluid feeding attachment which may be readily applied to a hollow drill steel, which attachment is frictionally held in position on the steel by the pressure of the fluid, and in which the pressure of the fluid 15 serves to form automatically a fluid-tight connection between the attachment and the hollow drill steel.

This invention consists more particularly in a fluid feeding nozzle having an annular 20 chamber in open communication with the fluid supply and with the interior of the hollow drill steel, the inner walls of the nozzle being forced snugly against the drill steel by the pressure of the fluid within the 25 said annular chamber.

A practical embodiment of my invention is represented in the accompanying drawings, in which—

Figure 1 represents a hammer drill in side 30 elevation with the improved fluid feeding attachment applied thereto, Fig. 2 is a detail view taken at right angles to Fig. 1, Fig. 3 is a section taken in the plane of the line A—A of Fig. 1, looking in the direction of 35 the arrows, Fig. 4 is a section taken in the plane of the line B—B of Fig. 2, looking in the direction of the arrows, Fig. 5 is an enlarged detail plan view of the attachment, Fig. 6 is a section taken in the plane of the 40 line C—C of Fig. 5, looking in the direction of the arrows, Fig. 7 is a plan view of a modified form of attachment suitable for use in connection with round, hollow drill steels, and Fig. 8 is a section taken in the plane of 45 the line D—D of Fig. 7, looking in the direction of the arrows.

The hollow drill steel is denoted by 1 and its longitudinally arranged axial bore by 2. Transversely arranged holes 3 lead from the 50 bore 2 through to the exterior of the drill steel at a distance from its striking end and at a point beyond the drill.

The fluid feeding attachment comprises a hollow nozzle having a fluid inlet tube 4, 55 outer walls 5, inner walls 6 and an annular

chamber 7, formed between said outer and inner walls.

The inner walls 6 of the nozzle are fitted to embrace and snugly engage the hollow 60 drill steel 1 and holes 8 are formed through the inner wall 6 so that when the nozzle is in proper position, open communication is established from the annular chamber 7 through the holes 8 in the inner walls 6 and the holes 3 in the drill steel to the longitudinal bore 2 of the said drill steel. 65

The inner walls 6 of the nozzle are elastic and are shaped to conform to the exterior of the drill steel in connection with which the attachment is to be used. 70

The whole nozzle may be formed of rubber and may be strengthened, if so desired, by incorporating therein an annular series of longitudinally arranged stiffening pieces 9 of metal or other desired material which 75 pieces serve to connect the outer and inner ends of the said nozzle.

It will thus be seen that the fluid which is being fed to the interior of the hollow 80 drill steel through the nozzle, will exert its pressure on the inner walls 6 of the nozzle to hold the walls snugly in engagement with the drill steel and thus serve the double purpose of making a fluid-tight connection 85 between the nozzle and the drill steel and also of tending to hold the nozzle in position on the steel.

Additional means may be employed for preventing the undue displacement of the 90 nozzle, which means, in the present instance, is shown as a wire stop 10 having its branches 11, 12, hinged to the front end of the drill cylinder 13 so that the stop when swung into its operative position will engage the drill steel at a point a slight distance 95 beyond the nozzle.

The tendency of the branches 11, 12, to spring toward each other will yieldingly hold their inwardly turned ends 14, 15, in engagement with their sockets in the front 100 end of the drill cylinder 13.

In Figs. 1 to 6 inclusive, the nozzle is shown as adapted for use in connection with a drill steel of angular cross section and in 105 Figs. 7 and 8 as being adapted for a drill steel round in cross section but it is to be understood that this nozzle is to be so made that its inner walls will fit steels of any cross sectional shape.

It will be seen that the tube 4 of the nozzle 110

will form a suitable handle for assisting in the manipulation of the drill. It will also be noted that where a drill steel round in cross section is used, the steel could rotate 5 within the nozzle without destroying the fluid tight connection between the steel and nozzle.

What I claim is:—

1. A fluid feeding attachment for hollow 10 drill steels comprising a nozzle of elastic material having inner and outer walls inclosing an annular chamber, its inner wall being arranged to be held in fluid-tight engagement with the steel by the pressure of 15 the fluid within the chamber, and stiffening pieces incorporated in said nozzle.
2. A fluid feeding attachment for hollow 20 drill steels comprising a nozzle of elastic material having inner and outer walls inclosing an annular chamber, its inner wall being arranged to be held in fluid-tight engagement with the steel by the pressure of the 25 fluid within the chamber, and an annular series of longitudinally arranged stiffening pieces incorporated in said nozzle.
3. The combination with a drill and its hollow steel, of a fluid feeding attachment

for the steel comprising a nozzle having integral inner and outer walls inclosing an annular chamber, the inner wall being elastic and arranged to be held in fluid-tight engagement with the steel by the pressure of the fluid within the chamber, and a stop carried by the drill for preventing the displacement of the nozzle.

4. The combination with a drill and its hollow steel, of a fluid feeding attachment for the steel comprising a nozzle having integral inner and outer walls inclosing an annular chamber, the inner wall being elastic and arranged to be held in fluid-tight engagement with the steel by the pressure of the fluid within the chamber and a swinging stop carried by the drill for preventing the displacement of the nozzle.

In testimony, that I claim the foregoing as my invention, I have signed my name in presence of two witnesses, this eighteenth day of January, 1909.

WILLIAM PRELLWITZ.
